TO NEW JERSEY OPTICAL CO., OF NEWARK, NEW JERSEY, A CORPORATION OF
NEW JERSEY.

EYEGLASS AND SPECTACLE MOUNTING.

1,173,151

Specification of Letters Patent. Patented Feb. 22, 1916.

Application filed December 28, 1915. Serial No. 68,989.

To all whom it may concern:

Be it known that we, EDGAR R. DURGIN and WAYNE S. SEARLES, citizens of the United States, and residents of Newark, 5 county of Essex, State of New Jersey, have invented certain new and useful Improvements in Eyeglass and Spectacle Mountings, of which the following is a specification.

10 Our invention has for its general object to provide an improved construction of means whereby the lugs to which the temple wires are secured and also the opposite ends of the bridges of eyeglasses and spectacles may be 15 more efficiently and economically attached to the lens rims.

A further and more specific object of our invention is to provide means whereby such parts may be more securely attached and 20 fastened to lens rims, particularly non-metallic rims, than heretofore, as far as we are aware, has been practicable.

Our invention also has for one of its objects to provide an improved construction of 25 fastening or securing means which may be attached or fastened to non-metallic rims without injuring the same or biting into the material thereof in a manner to impair the strength and durability thereof.

30 Other objects and advantages of our invention will be referred to in the detailed description thereof which follows or will be apparent from such description.

In order that our invention may be more 35 readily understood and its purposes and advantages more fully appreciated reference should be had to the accompanying drawing in which we have illustrated one form of a convenient embodiment of our invention.

40 It will be understood, however, that changes in the details of construction may be made within the scope of the claims without departing from our invention.

In the drawings:—Figure 1 is a side elevation of a lens rim provided with a device embodying our invention; Fig. 2 is a transverse section taken on the line 2—2 of Fig. 1 and showing the inner edge of said device attached to a lens rim; Fig. 3 is a transverse 50 sectional view, enlarged, taken on the line 3—3 of Figs. 2 and 4; Fig. 4 is a view similar to that shown in Fig. 2 but with the parts considerably enlarged; Fig. 5 is a sectional view taken on the line 5—5 of

Fig. 4; and Fig. 6 is a view of the parts 55 entering into the construction of our invention, said parts being separate from each other and ready to be assembled.

In the construction as illustrated we have shown but a single lens rim and a single attaching or fastening device embodying our invention but it will be understood that one of these fastening devices may be employed for each temple wire and also that two of such fastening devices may be employed in 65 connection with each bridge or spring.

Referring to the drawings, 1 designates a lens rim of non-metallic material having an inner groove 1^a to receive the edge of a lens and 2 designates an elongated part of 70 sheet metal bent and adapted to embrace a portion of the rim as illustrated. The said part 2 is curved longitudinally so as to conform to the peripheral curvature of the lens frame. Such curvature is best illustrated in Figs. 1 and 5.

In transverse section the body portion of the device 2 is substantially of U-shape as illustrated in Fig. 3. The inner edges of the part 2 are provided with undercut 80 notches 3 adapted to receive the projecting tongues 4 upon the opposite edges of a co-operating complementary strip 5. The part 2 having been placed in position upon the lens rim the plate 5 is placed in position intermediate the inner edges of the part or member 2 with the projecting tongues 4 in engagement with the notches 3. After having been thus positioned the parts 2 and 5 are acted upon by a proper tool to bend the 90 inner edges of the part 2 upon opposite sides of the notches 3 inwardly and slightly downwardly over the inner edges of the rim upon opposite sides of the groove 1^a. The strip 5 is also bent or curved both longitudinally and transversely so as to cause it to conform to the groove 1^a upon the inner side of the rim. After the parts 2 and 5 have been pressed or otherwise caused to conform to and clamp the rim at the point where 100 they surround the same, the tongues 4 extend laterally in directions transversely of the plane of the rim and are situated in the said notches 3 in substantial alinement with the inwardly bent edges of the part 2. In 105 the completed structure the edges of the device 2 intermediate the notches 3 are in abutting relation to the side edges of the strip 5.

intermediate and outside of the projecting tongues 4. The preferred relation of these abutting edges is shown at 10 in Fig. 3 of the drawing. It should be understood, however, that the relation of these edges may be changed without departing from the spirit and scope of our invention.

11 designates a stud or projection secured in any manner, as by soldering, to the outer 10 curved edge of the member 2. The stud 11 is provided with a slot 12 adapted to receive the inner end of a temple wire, not shown.

As already indicated, the part 2 and its coöperating strip or part 5 are adapted to 15 be employed not only for the purpose of providing means for connecting the temple wire lug or stud to the lens rim but is also adapted for and is used as a means for connecting the opposite ends of a spectacle 20 bridge or eyeglass spring to the inner edges of the rims of a pair of eyeglasses.

By the employment of our construction it will be observed that a portion of the rim is completely embraced or surrounded by 25 means of the part 2 and its coöperating and complementary strip or part 5. These parts coöperate to form in effect a sleeve within which a portion of the eyeglass rim is held, such sleeve conforming to the shape of the 30 particular portion of the rim where it is situated. By thus providing means for completely embracing the rim we are enabled to avoid the necessity of providing prongs or other parts which must be caused to bite 35 into or become embedded in the material of the lens rim in order that the same may be securely fastened or attached thereto. It is apparent, therefore, that our invention constitutes a valuable improvement in that it 40 prevents injury in any way to or impairment of the eyeglass or spectacle rim.

We claim:—

1. In an eyeglass mounting, the combination of a part bent so as to conform to a 45 portion of an eyeglass or spectacle rim, the inner edge of said part being provided with notches and a strip situated between the edges of said part and having projecting tongues in engagement with the said notches.

50 2. In an eyeglass mounting, the combination of a part bent transversely and longitudinally to embrace a portion of an eyeglass rim the inner edges of said part being provided with notches, and a strip situated 55 intermediate the inner edges of said part, said strip having tongues projecting from its side edges and being in interlocked engagement with the said notches, said strip being also bent transversely and longitudinally.

60 3. In an eyeglass mounting, the combination of a part consisting of sheet metal bent longitudinally and transversely so as to conform to a portion of an eyeglass or spectacle 65 rim embraced thereby, the inner edges of

said part being bent over the inner edges of the portion of the rim embraced thereby, the said inner edges of the said part being provided with undercut notches and a strip situated intermediate the inner edges of said part and being bent transversely and seated in a groove in the inner periphery of said rim, said strip having tongues projecting from its side edges which are in interlocked engagement with said notches. 75

4. In combination, an eyeglass rim, a part partially embracing a portion of said rim said part being bent transversely and longitudinally and being provided with undercut notches in its inner edges, and a member 80 situated intermediate the said inner edges and being also bent transversely and longitudinally, said member having projecting tongues in interlocked engagement with said notches, the edge portions of said part upon 85 opposite sides of said notches being bent inwardly over the inner edges of the said rim, and the said tongues extending outwardly into the said notches, the said part and member being clamped against said rim. 90

5. A fitting having a lens frame comprising a portion embracing the outer surface of a portion of said frame and a portion contacting with the inner surface thereof the said portions being interlocked with each 95 other and being clamped against said frame.

6. A metal fitting for a non-metallic eyeglass or spectacle frame said fitting having a portion fitting around the outer and side surfaces of a portion of said frame and being longitudinally curved to fit the peripheral curvature of the frame and also having a portion longitudinally and transversely curved situated upon the inner side of said frame, said portions being interlocked with 100 each other and being clamped around the said frame. 105

7. Blanks for an eyeglass fitting one of said blanks consisting of a sheet metal portion having notches formed in the side edges thereof, said portion being adapted to be longitudinally and transversely curved to fit the rim of an eyeglass frame and the other of said blanks having projecting tongues upon the side edges thereof said blank being adapted to be bent longitudinally and transversely and the said tongues being adapted to interlock with the said notches, substantially as described. 115

8. In a fitting for an eyeglass or spectacle 120 rim, the combination of a transversely and longitudinally bent sheet metal member having undercut notches in the side edges thereof the edges of said member being bent inwardly to engage the inner edges of the rim upon the opposite sides of the lens groove therein and a sheet metal strip situated intermediate the edge portions of said member said strip being bent longitudinally and transversely and being provided with 125 130

tongues in interlocked engagement with the said notches the said member and strip clamping the inclosed portion of said rim and the first-named member having a lug 5 or projection thereon to which may be connected any desired part of an eyeglass or spectacle mounting.

In testimony that we claim the foregoing as our invention we have hereunto signed our names this 24 day of December, A. D. 10 1915.

EDGAR R. DURGIN.
WAYNE S. SEARLES.
